RUFFLING ATTACHMENT FOR SEWING MACHINES

Victor J. Sigoda, Great Neck, N. Y., assignor to Man-Sew Corp., New York, N. Y., a corporation of New York

Application November 6, 1941, Serial No. 417,995

8 Claims. (Cl. 112—134)

This invention relates to ruffling or gathering attachments for sewing machines and has for its general object and purpose to provide a simple and comparatively inexpensive attachment of this character, readily applicable to sewing machines of well known standard makes and which embodies certain practical improvements resulting in important advantages in the use and operation of the attachment disclosed in Patent No. 2,245,877 issued June 17, 1941, to Man-Sew Pinking Attachment Corp.

It is a more particular object of this invention to provide a new mounting and arrangement of the oscillatory ruffling blade with respect to the vertically reciprocating needle of the sewing machine so that the operator is afforded a clear and unobstructed vision of the work as it is fed to the sewing machine presser foot. To this end, the invention is essentially characterized by the mounting and arrangement of the guide for the material to be ruffled at the rear side of the presser foot together with the oscillatory ruffling blade which cooperates with said guide to form the ruffles or folds and feed the same through an opening in the presser foot to the base fabric in position to be stitched to the latter by the vertically reciprocating needle.

It is also an additional object of the invention to provide improved actuating means for the ruffling blade including certain relatively adjustable parts whereby the movement of the blade may be regulated or controlled to produce contrastingly variegated sections of ruffling and a finished product of novel and ornamental design.

With the above and other objects in view, the invention comprises the improved ruffling attachment for sewing machines as well as the form, construction and relative arrangement of its several parts, as will hereinafter be more fully described, illustrated in the accompanying drawings and subsequently incorporated in the subjoined claims.

In the drawings wherein I have disclosed one simple and practical embodiment of the invention and in which similar reference characters designate corresponding parts throughout the several views:

Fig. 1 is a front side elevation of a sewing machine having my improved attachment applied thereto, the housing means for a part of the operating mechanism being shown in section.

Fig. 2 is an end elevation with the face plate of the housing for the ruffer actuating mechanism removed and showing the ruffling blade in retracted position.

Fig. 3 is a top plan view partly broken away and partly in section.

Fig. 4 is an end elevation showing the variable speed operating means for the ruffer actuating mechanism.

Fig. 5 is a view similar to Fig. 2, showing the ruffling blade at the end of its forward ruffle forming stroke.

Fig. 6 is a detail vertical section through the sewing machine presser foot with the ruffling blade in the position of Fig. 5.

Fig. 7 is a horizontal sectional view taken on the line 1—7 of Fig. 6.

Fig. 8 is a detail perspective view of one form of ruffling blade used in connection with the zigzag sewing machine.

Fig. 9 is a similar view of another form of blade used in connection with a two-needle sewing machine.

Fig. 10 shows the ruffling blade as used in connection with a single needle sewing machine, and

Fig. 11 is a plan view illustrating ruffling as executed by the machine in sections of variegated design.

Referring in detail to the drawings in which I have illustrated a well known zigzag type of sewing machine, 5 indicates the usual hollow arm extending horizontally in one direction from the upper end of a hollow vertical pedestal 6 which is integrally formed with or suitably mounted upon the machine bed plate 7. The other end of the arm 5 is provided with the usual guide head 8 for the vertically reciprocating needle bar 9 carried by the laterally vibratory frame 10 mounted in the usual manner at its upper end within the guide head 8 and actuated by the pitman bar 11 through suitable operating connections with the main shaft 12 of the sewing machine which extends through the arm 5. One end of this shaft is operatively connected by any conventional means (not shown), with the needle bar 9, said shaft at its other end having the usual belt wheel 13 for connection with a suitable driving motor.

In applying the present attachment, the usual face plate closing the end of the guide head 8 is removed and the housing 14 which encloses a part of the actuating means for the ruffling blade is substituted therefor. This housing and said actuating means are similar to that shown in the above-referred to issued patent and includes the shaft 15 suitably mounted in the lower front end of said housing and projecting at one of its ends from the inner side thereof. Within the housing, the lower end of a lever 16 is rigidly attached to the shaft 15 and extends upwardly

therefrom, the upper end portion of said lever having a longitudinal slot 17 receiving the adjustable slide block 18 which is also slidably mounted upon the rod 19 having a fixed connection at one of its ends with one end of a shaft 20 journaled in the inner side wall of said housing. As shown in Fig. 3 of the drawings, this shaft extends longitudinally along the rear side of the arm 5 and is operatively connected at its other end with the main shaft of the machine by a variable speed mechanism through which rocking motion is transmitted to said shaft, and which will be hereafter more fully referred to.

The means for adjusting the slide block 18 along lever 16 and rod 19 and with relation to the axis of the shaft 20, whereby the oscillating motion of the shaft 15 is controlled, is also quite similar to that shown in the issued patent and comprises the shaft 21 journaled at one end in the inner side wall of the housing 14 and operated by a treadle or other suitable manually operable means. Within the housing the arm 22 is fixed to said shaft at one end and connected at its other end by means of the link 23 with the slide block 18. A coiled wire spring 24 on the shaft 21 has one of its ends bearing downwardly on the arm 22 and the other end in contact with the top wall of the housing 14. The arm 22 is moved upwardly against the action of the spring 24 to adjust the slide block 18 towards the upper end of slot 17 by means of a rod 25 having a loop formed on its lower end engaged with pin 26 carried by the arm 22. The upper end of this rod extends through an opening in the top wall of the housing 14 and has a nut 27 threaded thereon. Thus it will be evident that by the proper adjustment of this nut, the slide block 18 may be shifted in the slot 17 and along the rod 19 and disposed in a predetermined position relative to shaft 20, thus determining the extent or degree of oscillating motion of the shaft 15. This constitutes the principal means for varying the stroke of the oscillatory ruffling blade.

At the rear side of the frame 10 and needle bar 9, the usual presser foot bar 28 is vertically movable in the guide head 8 and has the presser foot 29 attached to the lower end thereof. As shown in Fig. 6 of the drawings, this presser foot includes the horizontal portion 30 having the upwardly inclined toe 31 at its forward end. At its rear end the part 30 is integrally formed with the vertically extending shank 32. Upon the upwardly and rearwardly inclined bracket member 33 attached to the rear side of the shank 32 the rectangular tubular guide 34 for the braid or tape to be ruffed is rigidly fixed, the lower end of said guide being positioned in the upper end of the opening 35 formed in said shank.

To the front side of the shank 32 of the presser foot a downwardly inclined plate 36 is fixed at its upper end, said plate at its lower end terminating immediately above the opening 37 in the horizontal part 30 of the presser foot and closely adjacent to the path of movement of the reciprocating needle 38.

Upon the lower rear end of the housing 14 at the inner side thereof, the downwardly and rearwardly extending arm 39 is pivotally mounted as at 40. A lever 41 is adjustably connected at its upper end with said arm by means of a threaded pin or stud 42 fixed to said lever and movable in a slot 43 provided in the arm 39. A nut threaded on the pin 42 adjustably clamps the upper end

of the lever rigidly to the arm. The lower end of said lever 41 carries the fixed pin or stud 44 upon which the rear end of the ruffling blade 45 is pivotally mounted. The forward end of this blade is yieldingly urged upwardly by the coil spring 45' on the pin 44 and against the rear side of the inclined plate 36 fixed to the presser foot.

To the end of the shaft 15 at the inner side of housing 14, the downwardly extending arm 46 is rigidly fixed and is connected by means of link 47 to the forward end of a link 48, the rear end of which is pivotally connected at 49 with a second arm 39' fixed to the pivot pin or rod 40. Link 47 is also adjustably connected with arm 46 by the pin 50 movable in slot 51 in said arm and having a clamping nut threaded thereon. Thus the pivotal connection 52 between the links 47 and 48 may be variably positioned relative to the axis of shaft 15 to provide a further adjustment of the stroke or throw of the ruffling blade 45. By adjusting the lever 41 relative to arm 39, the angle of the blade is changed and the energy stored in the spring 45' regulated to change the pressure of the forward end of the blade against the material, as may be required for different kinds of fabrics and in order to insure a desired form of the folds or ruffles as they are fed to the needle 38 and upon the work in the operation of said ruffling blade.

As will be noted from reference to Fig. 6, the ruffling blade has free movement through the opening 35 in the presser foot shank and its forward end is yieldingly urged upwardly against the inner surface of the plate 36. Of course, the machine is equipped with the usual feed mechanism, a part of which is indicated at F, which intermittently feeds the base fabric B beneath the presser foot. Therefore, the tape or braid T stitched to said fabric will be drawn through the guide 34 in the intermittent movements of said fabric. The forward end of the ruffling blade moving downwardly, in cooperation with the plate 36, engages and forms a fold T' in said tape which is projected through the opening 37 in the presser foot and upon the upper surface of the base fabric.

As shown in Fig. 8, the ruffling blade 45 is formed at its forward end with the spaced notches or recesses 53 which alternately receive the needle 38 in its downward strokes in the vibratory motion of the frame 10. Preferably, the end edges of the blade 45 at opposite sides of the slots 53 are serrated or toothed as at 54 to secure a gripping engagement with the tape or braid T.

The ruffling blade shown in Fig. 9 is used in connection with the two-needle sewing machine and is also provided at its forward end with the spaced slots or recesses 53', which are somewhat more widely spaced apart than the notches 53 shown in Fig. 8. The ruffling blade shown in Fig. 10 to be used in a single needle sewing machine is provided with a single central needle receiving slot 53a.

While the power transmission shaft 20 for the ruffler actuating mechanism might be operatively connected with the sewing machine needle bar substantially as illustrated in the issued patent above referred to, I preferably provide a variable speed operating mechanism for said shaft. The latter, however, is not herein claimed as it forms the subject matter of my pending application for patent, Ser. No. 378,509, filed February 12, 1941. It will, therefore, suffice for the purpose of this

explanation to state that this mechanism is arranged at the right hand end of the sewing machine and is enclosed within a suitable housing 55 supported upon the machine pedestal 7, said mechanism including the gear elements 56, 57 and 58, the latter of which is fixed to the end of the main shaft 12. Within said housing and to the end of the rock shaft 20, an arm 59 is rigidly attached and carries a slidably adjustable pin 60 which is selectively connectible with said gear elements whereby rocking motion is transmitted to the shaft 20 at variable speeds from the main needle operating shaft 12 of the machine.

From the above description, it will be evident that as the oscillatory ruffling blade, and the braid or tape guide is mounted entirely at the rear of the needle bar 9, the operator has a clear and unobstructed vision of the needle and presser foot of the machine and of the base fabric B, as it is fed rearwardly beneath said presser foot. By the provision of the additional adjustable connection between the ruffling blade and the operating shaft 15 therefor, the movements of the blade may be further controlled and changed so as to produce various different designs of the ruffles or folds, or variegated sections of continuous ruffling applied to a base fabric, as indicated in Fig. 11 of the drawings. Thus at the left in this figure, the section E is composed of ruffles or folds which are relatively wide and provide a discontinuous end edge of each fold across the width of the tape. The ratio is 1 to 1 with maximum feed movement. The intermediate section D consists of comparatively narrow folds or ruffles, the transverse edges of which are continuous. The ratio is 4 to 1 with a short feed movement. The right hand section C has ruffles of an intermediate width with longer feed movement and a ratio of 2 to 1. Of course, it is also possible, by making the proper adjustments to produce further variations in the width and form of the individual ruffles, and also to provide an unruffled section, without stopping the operation of the machine by shifting the slide block 18 into coaxial relation with the shaft 20. It will thus be seen that I have made important practical improvements in the attachment of the issued patent whereby the efficiency and commercial utility of such attachments is materially enhanced.

In the foregoing description and accompanying drawings, I have disclosed an embodiment of the invention, which in actual practical operation has given excellent results. However, it is to be understood that such disclosure is largely illustrative and that the essential features of the present invention which characterizes its novelty may also be incorporated in various other structural forms. Accordingly, the privilege is reserved of resorting to all such legitimate changes in the form, construction and arrangement of the various elements as may fairly be comprehended within the spirit and scope of the appended claims.

I claim:

1. In combination with a sewing machine including a vertically reciprocating needle and a presser foot having a work engaging part provided with an opening; ruffling mechanism comprising means for folding the material to be ruffled, said means including a movable blade having one of its ends positioned above said part of the presser foot for movement into and out of said opening, and a fixed member carried by the presser foot and positioned above said opening and with which said end of the blade cooperates in its movement in one direction to fold said material downwardly

through the opening of the presser foot and in directly superimposed position upon the work.

2. In combination with a sewing machine including a vertically reciprocating needle and a presser foot having a work engaging part provided with an opening; ruffling mechanism comprising means for folding the material to be ruffed, said means including a movable blade having one of its ends positioned above said part of the presser foot for movement into and out of said opening, a fixed member carried by the presser foot and positioned above said opening and with which said end of the blade cooperates in its movement in one direction to fold said material downwardly through the opening of the presser foot and in directly superimposed position upon the work, and means carried by the presser foot for feeding the material to be ruffed between said fixed member and the movable ruffling blade.

3. In combination with a sewing machine including a vertically reciprocating needle and a presser foot having work engaging and vertical shank portions each provided with an opening; ruffling mechanism comprising a ruffling blade operatively mounted rearwardly of the presser foot, extending forwardly through the opening in said shank portion and having its forward end positioned for movement into and out of the opening in the work engaging portion of the presser foot, a member carried by the presser foot with which said end of the blade cooperates in its forward movement to fold the material to be ruffed downwardly through said latter opening and in directly superimposed position upon the work, and additional means carried by the presser foot for directing said material between said member and the ruffling blade.

4. In combination with a sewing machine including a vertically reciprocating needle and a presser foot having work engaging and vertical shank portions each provided with an opening; ruffling mechanism comprising a ruffling blade operatively mounted rearwardly of the presser foot, extending forwardly through the opening in said shank portion and having its forward end positioned for movement into and out of the opening in the work engaging portion of the presser foot, a member carried by the presser foot with which said end of the blade cooperates in its forward movement to fold the material to be ruffed downwardly through said latter opening and in directly superimposed position upon the work, and a member mounted on the rear side of the presser foot shank to receive and direct the material to be ruffed through the opening therein and position the same relative to the end of the ruffling blade and said cooperating member.

5. In combination with a sewing machine including stitch forming mechanism; ruffling mechanism comprising a movable ruffling blade, actuating means for said blade including a rock shaft and means for operating said shaft in timed relation with the stitch forming mechanism, a lever pivotally supported at its upper end, means operatively connecting one end of the ruffling blade with the lower end of said lever, an arm fixed to said rock shaft, pivotally connected relatively movable links, means pivotally connecting one of said links with said lever, and means adjustably connecting the other of said links with said arm to variably space the pivotal connection between said links from said rock shaft and regulate the extent of oscillating motion of said lever and the ruffling blade.

6. In combination with a sewing machine in-

cluding stitch forming mechanism, ruffling mechanism and actuating means therefor including a rock shaft and means for operating said shaft in timed relation with the stitch forming mechanism, a pair of spaced apart arms rigidly connected at one of their ends to a common pivot rod, means operatively connecting the rock shaft with one of said arms, a movable ruffling blade, a lever pivotally connected at one of its ends to one end of said blade, a spring resisting pivotal movement of the blade in one direction, a fixed member towards which the other end of the blade is yieldingly urged by said spring to engage and fold the material to be ruffed, and means connecting said lever at its other end with the other of said arms for lengthwise adjustment of the lever relative to said arm to change the angle of the ruffling blade relative to the lever and said fixed member and vary the energy stored in said spring whereby the pressure of the ruffling blade against the material is regulated.

7. In combination with a sewing machine presser foot having a vertical shank portion and a horizontal work engaging portion, each provided with an opening, ruffling mechanism including a ruffling blade operatively mounted behind the presser foot for reciprocation through the opening in the presser foot shank, and a fixed member

downwardly inclined from the front side of said shank and terminating closely adjacent to the opening in said work engaging portion of the presser foot, said blade cooperating with said member to form a fold in the material to be ruffed and direct the same downwardly through the latter opening into directly superimposed position upon the work.

8. In combination with a sewing machine presser foot having a vertical shank portion and a horizontal work engaging portion, each provided with an opening, ruffling mechanism including a ruffling blade operatively mounted behind the presser foot for reciprocation through the opening in the presser foot shank, a fixed member downwardly inclined from the front side of said shank and terminating closely adjacent to the opening in said work engaging portion of the presser foot, said blade cooperating with said member to form a fold in the material to be ruffed and direct the same downwardly through the latter opening into directly superimposed position upon the work, and means mounted upon the rear side of the presser foot shank to direct the material through the opening therein and position the same relative to said fixed member for engagement by the ruffling blade.

VICTOR J. SIGODA.
